Primary Examiner — Nathan M Johnston(57) CLAIM

The ornamental design for a toilet plunger and brush kit, as shown and described.

DESCRIPTION

FIG. 1 is a perspective view of a toilet plunger and brush kit showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the toilet plunger and brush kit.
The broken lines in the drawings depict portions of the toilet plunger and brush kit that form no part of the claimed design.
